UNITED STATES PATENT OFFICE.

ALBERT C. GRUNWALD, OF RIVER FOREST, ILLINOIS, ASSIGNOR TO PRECISION METAL WORKERS, OF CHICAGO, ILLINOIS, A CORPORATION OF ILLINOIS.

ELECTRIC SWITCH.

Application filed December 24, 1921. Serial No. 524,699.

To all whom it may concern:

Be it known that I, ALBERT C. GRUNWALD, a citizen of the United States, and resident of River Forest, in the county of 5 Cook and State of Illinois, have invented a certain new and useful Improvement in Electric Switches, of which the following is a full, clear, concise, and exact description, reference being had to the accompanying drawings, forming a part of this specification.

My invention relates to an electric switch for stop signal systems for the display of an indicating light at the rear of automobiles and other vehicles.

The objects of my invention are improvements in the apparatus and mechanism; to provide a more efficient and more correctly operating signal, and at the same time to 20 improve the apparatus from the standpoint of endurance and economy in manufacture.

My invention is illustrated in the accompanying drawing, in which—

Figure 1 illustrates the signal mounted 25 upon the fender of an automobile and connected with a switch and source of current in the conventional way;

Figure 2 is an elevation of the circuit changing switch mechanism, showing its application to a brake rod;

Figure 3 is a section through the switching mechanism on the line 7—7 of Figure 2;

Figure 4 is an illustration of the circuit changing parts of the switch mechanism of 35 Figure 7 with covers removed.

The switching member illustrated generally at 42 in Figure 1, and in detail in Figs. 2, 3 and 4, comprises a mounting plate 43 having a central portion 44 slightly raised 40 above the plane of the surface upon which the mounting plate is attached. A pair of end plates 45 and 46 support a cylinder 47 of insulating material, and also support a shaft 48, which by its rotation, performs 45 the switching function. If desired, each of the plates 45 and 46 may be provided with inwardly turned ears X which overlie the adjacent ends of cylinder 47. Moreover a bar Y preferably connects plates 45 and 50 46 as shown. These end plates and the cylinder form a housing which, in operation, is preferably filled with an insulating lubricant which also prevents moisture from entering the cylinder. Surrounding the shaft

48 and in pressed-on engagement therewith 55 is a cylindrical member 49 of insulating material encased within a metallic cylinder 50, the latter having a small section removed at the position 51. This cylinder is preferably attached to the insulating member 49 60 by means of a pressing operation, which, through conical dies, contracts the ends of the metal cylinder as at 52.

An operating handle 54 is attached to one end of the shaft 48, the said handle having 65 a portion thereof, as at 55, formed into a section of a cylinder serving as a guide and support for the spring 56, which, by attachment to the arm 54 at 57, and to the end plate 46 at 58, tends to rotate the arm and 70 shaft in a counter-clockwise direction, as viewed in Fig. 2. The end of the spring 56 merely extends through the arm 54, resulting in a readily removable attachment, 75 so that the spring can be originally assembled or replaced with ease. Within the cylinder 47, a pair of contacting members 80 60 and 61 are mounted; these members being constructed of spring metal, each formed with a bead 62 extending longitudinally of the cylinder and engaging slots 63 therein. The portions of the spring members 60 and 61 which lie adjacent the inner surface of the cylinder have perforations in them through which the stem portions of binding posts 85 65 extend, the heads 66 on the inner ends of the stems being provided with projections registering with the inner concave portions of the beads 65, and being drawn firmly 90 into position by knurled nuts 67 which thread upon the externally projecting portions of the stems. The contacting member 60 bears continually against the surface of the metallic cylinder 50, while the contacting member 61 normally registers with the 95 position 51 at which the cylinder 50 is cut away, so that until the cylinder is turned from its normal position, the circuit is not completed between the contacting members 60 and 61, but when the cylinder is turned 100 a predetermined amount from its normal position, both of the contacting members 60 and 61 register with the cylinder and thus the circuit is completed between the binding posts 65.

The end plate 46 is provided with an upturned lug 70 which forms a normal abutment for the handle 54 to hold the shaft 48

- and cylinder 50 in the open circuit position. The free end of the handle 54 may be attached to any form of operating mechanism, and for that purpose is provided with an 5 opening 71 into which a link 72 may be attached, the other end of the link being attached to any suitable form of operating mechanism which, as shown in Figs. 1 and 10 2, is a brake rod 73.
- 15 The usual storage battery of the automobile is connected in series with the switch 42 and the lamp filament 84 so that upon the closure of the switch contacts, the lamp is caused to glow and display the "stop" signal. Under the arrangement illustrated in Fig. 1, the "stop" signal is displayed every 15 time the brake pedal is depressed.

20 Although I have shown and described my invention with respect to certain details of construction, it is to be understood that these details may be modified within the skill of a mechanic without departing from the spirit or scope of my invention.

25 What I claim is:

1. In a switch for a stop signal mechanism, a metal base plate adapted to be attached to a flat surface, shaft bearing plates carried by said base plate, said bearing plates being parallel to each other and spaced apart, a hollow cylinder of insulating material clamped between said shaft bearing plates and with the latter constituting a closed housing, brushes carried by the 30 inner surface of said hollow cylinder, a shaft 35 extending through said hollow cylinder and journaled in said bearing plates, a cylinder of insulating material carried by said shaft and disposed in said hollow cylinder, a conducting sleeve disposed around and fixed to 40 said shaft carried cylinder, said conducting sleeve having a portion thereof cut away to provide a recess, and spring means associated with said shaft and normally holding said sleeve in a position such that one of 45 said brushes extends through said recess and bears against said shaft carried insulating cylinder, the other brush at all times bearing against said conducting sleeve.
2. In a switch for a stop signal mechanism, a substantially oil-tight housing comprising a hollow cylinder of insulating mate-

rial and plates which are clamped against the ends of said hollow cylinder, a cylinder of insulating material mounted for rotary movement within said first-mentioned cylinder, 55 a conducting sleeve carried by said rotary cylinder and having a recess therein, a shaft whereon said rotary cylinder is mounted, said shaft being journaled in said plates, a pair of brushes carried on the inner surface of said first-mentioned cylinder, one of 60 said brushes being continuously in contact with said conducting sleeve, spring means normally holding said rotary cylinder in such position that the other brush extends 65 through the conducting sleeve recess, and bears against the insulating material of the cylinder by which said sleeve is carried, and means for moving the rotary cylinder to cause said last-mentioned brush to contact 70 with the conducting sleeve.

3. In a switch forming part of a stop signal mechanism, an oil-tight housing, a non-conducting lubricant within said housing, a cylindrical member of non-conducting material mounted for movement within said housing, said non-conducting cylindrical member lying within and carrying a sleeve of conducting material having a portion thereof cut away to expose a portion of the 75 cylindrical surface of the said non-conducting cylindrical member, a pair of brushes carried by said housing and adapted to cooperate with said conducting sleeve, one of 80 said brushes being at all times in contact with said sleeve, spring means normally holding said cylindrical member and said sleeve in a position wherein the other brush engages the aforesaid exposed surface of the 85 cylindrical member and lies out of electrical engagement with said sleeve, and means for moving said cylindrical member and said sleeve against the action of said spring to effect electrical connection between the sleeve 90 and said last mentioned brush.

95 In witness whereof, I hereunto subscribe my name this 12th day of December, 1921.

ALBERT C. GRUNWALD.
